(57) **CLAIM**

The ornamental design for a furniture leg protector, as shown and described.

DESCRIPTION

FIG. 1 is a front view of a furniture leg protector showing my new design;

FIG. 2 is a rear view of the furniture leg protector;

FIG. 3 is a right side view of the furniture leg protector;

FIG. 4 is a left side view of the furniture leg protector;

FIG. 5 is a top view of the furniture leg protector;

FIG. 6 is a bottom view of the furniture leg protector;

FIG. 7 is a top front side perspective view of the furniture leg protector; and,

FIG. 8 is a top front side perspective view of multiple furniture leg protectors in an alternative position while in use.

The broken lines in FIGS. 1 and 7 are illustrative of portions of the device forming part of the claimed design. The broken lines in FIG. 8 are illustrative of environmental structure forming no part of the claimed design.

1 Claim, 4 Drawing Sheets
